Primary Examiner — Susan E Krakower*Assistant Examiner* — Lisa A Grabenstetter*(74) Attorney, Agent, or Firm* — Buchanan Ingersoll & Rooney PC(57) **CLAIM**

The ornamental design for a sanitary article, as shown and described.

DESCRIPTION

FIG. 1 is a top plan view of a sanitary article showing my new design.

FIG. 2 is a bottom plan view thereof.

FIG. 3 is a front view thereof.

FIG. 4 is a rear view thereof.

FIG. 5 is a right side view thereof; and,

FIG. 6 is a left side view thereof.

The broken lines and interior unshaded surface in FIG. 2 represents an unclaimed portion of the design.
